[57] CLAIM

The ornamental design for a container, as shown and described.

DESCRIPTION

FIG. 1 is a perspective view of the container, showing my new design;

FIG. 2 is a side elevational view thereof;

FIG. 3 is a side elevational view thereof, 90° relative to the elevational view of FIG. 2;

FIG. 4 is a top plan view thereof;

FIG. 5 is a bottom plan view thereof; and,

FIG. 6 is a cross-sectional view thereof taken along lines 6—6 of FIG. 2.
